REMOVABLE HEAD FOR METAL CONTAINERS.

Application filed October 31, 1925. Serial No. 65,925.

This invention relates to removable heads for metal containers and has for its object to provide a removable head and securing means therefor which is simple in construction and which can be economically manufactured, the head and its securing means being so constructed that the head is fluid tight and capable of resisting rough usage.

A further object of the invention is to provide a contractible clamping band which is engageable with the head at the open end of the container and with the body of the head within the chime in such manner as to exert an inward pressure on the head when the ring is contracted.

A further object is to so form the contractible band and to so secure the ends of the band that the ring when tightened is securely held against distortion.

A further object is to provide a contractible band in which the ring contracting means is positioned upon the interior of the ring contracting means is positioned upon the interior of the ring within the chime and in the depressed portion of the head.

The following description and accompanying drawings set forth in detail certain means embodying the invention, the disclosed means, however, constituting but one of the various mechanical forms in which the principle of the invention may be employed.

Reference should be had to the accompanying drawings forming a part of the specification in which Fig. 1 is a side elevation of a metal container in the form of a steel drum with the improved head applied thereto; Fig. 2 is a fragmentary axial section through an edge portion of the container and removable head and through the clamping band; Fig. 3 is a section similar to Fig. 2 showing the clamping band as it is being slipped into place on the head; Fig. 4 is a plan view of the clamping band; Fig. 5 is a fragmentary top plan view showing the band tightening and fastening means.

Referring to the accompanying drawings, the metal container to which the removable head is applied has a cylindrical wall 1 which is open at one end, the open end having applied thereto a bead ring 2 the inner edge of which is positioned against a circumferential bead 3 formed in the wall.

The bead ring 2 is an endless band which fits upon the exterior of the container and the bead 3 has a substantially square shoulder 4

on its outer side against which the inner edge of the ring 2 engages. The ring 2 is retained in place by an out-turned flange 5 formed by bending the edge portion of the body 1 outwardly over an outwardly rolled bead 6 formed at the upper edge of the band 2.

A head 7 fits within the open end of the container, the head 7 being cupped to provide an upstanding cylindrical outer portion 8 of a diameter such that it fits snugly within the body 1. The marginal portion of the head is bent outwardly from the outstanding portion 8 to form a flange 9 which overlies the flange 5 of the body of the container. A packing strip is interposed between the flanges 5 and 9 to provide a fluid tight seal between the head and body of the container when the head is pressed inwardly. For pressing the head 7 inwardly to compress the packing 10 between the flange 9 of the head and the flange 5 of the body, a contractible clamping band 11 is employed, the band 11 being of channel shape in cross section with the channel opening laterally with respect to the plane of the band so that the band can be slipped in an axial direction into place on the head of the container. The band 11 is formed with an inner flange 12 which is substantially cylindrical and of a diameter such that it can be slipped within the upstanding portion 8 of the head. The band 11 is also provided with an outer flange 13 which is shorter than the flange 12 and which is inclined inwardly toward the flange 12.

There is sufficient space between the edge of the flange 13 and the flange 12 to permit the band to slip down over the bead 6 when the band 11 is expanded as shown in Fig. 3 of the drawing and, when the band is contracted after it has been put in place, the inwardly extending flange 13 bears against the outer face of the bead 6 causing the band to be drawn inwardly toward the head and exert a pressure thereon.

The band 11 is a transversely split band, being severed at one point, and having lugs 14 rigidly secured to the adjoining ends. The ends of the band are drawn together to contract the ring by means of a bolt 15 passing through the lugs 14 and having a nut 16 thereon which may be tightened to draw the lugs toward each other. In order to enable the band to be drawn more tightly against the bead and to more rigidly seam the ends of the band together, the lugs 14 inwardly of

the bolt 15 are provided with protuberances 17 which are brought into contact when the nut 16 is tightened so that the point of engagement of the two protuberances 17 becomes a fulcrum point about which the adjacent ends of the band are moved by the nut as it is tightened. The lugs 14 being in contact at their inner ends and held tightly pressed toward each other by the bolt 15 provide a very rigid connection for the ends of the band. As the band is contracted, the inwardly inclined flange 13 engaging the surface of the bead 6 forces the band bodily inward causing the flange 12 which bears against the body of the head 7 within the upstanding portion 8 thereof to exert a heavy thrust against the head pressing the same inwardly and causing the flange 9 to be drawn tightly against the packing 10. The clamping bolt 15 is preferably substantially in the plane of the portion of the flange 13 which bears against the bead 6 so that there is a maximum resistance to the spreading of the band at the point where the thrust is exerted on the band. The flange 13 at all points intermediate the ends of the band will be very rigid by reason of the fact that any outward spreading of the flange will require elongation thereof and inasmuch as the band is very rigidly held substantially in the plane of engagement between the bead and flange where the outward thrust is applied the band will be maintained in tight engagement with the bead and may be subjected to much rough usage without impairing the fluid tight seal between the container and head. It should be noted that the clamping band is so designed that only one flange, namely, the bead engaging flange, has a thrust thereon which tends to distort it, and that the band tightening and fastening means is in substantially the plane of engagement of the flange with the bead where it exerts a maximum resistance to the spreading of the flange.

45 The portions of the clamping band intermediate the bead engaging flange 13 and the flange 12 are clear of the bead and of the marginal flange 9 of the head so that the inward movement of the band in tightening is not interfered with and so that the thrust upon the head is transmitted through the flange 12, the clamping action being due solely to the pressure exerted against the body of the head by the edge of the flange 12 bearing against it. The clamping ring since it is seated on the body of the head and extends over the overlapping edges of the head and body forms a very rigid chime for the barrel and at the same time greatly strengthens the head since it holds the depressed portion thereof against distortion.

50 An important feature of the present invention is that the packing 10 is protected against injury due to impact against the retaining band. If a barrel should roll off of a plat-

form and drop upon the end to which the removable head is attached the retaining band is subjected to a terrific impact at the point where it strikes the floor and in barrels in which the retaining band bears against the flange of the head which rests upon the packing, the packing is very likely to be ruptured by the impact causing a leak. The retaining band of the present invention, however, does not bear upon the flange of the head which rests upon the packing and the impact on the band when the barrel is dropped, instead of being directly transmitted to the packing is transmitted through the flange 12 of the band to the body of the head within the marginal upstanding flange 8 and through the resilient sheet metal head to the packing so that the pressure due to impact is in part dissipated due to the resiliency of the head and, instead of being applied to one point to the packing it is distributed through a considerable length of the packing, enabling the packing to withstand impacts which would otherwise damage the same to such an extent that the barrel would be no longer fluid tight.

Having described our invention, we claim:

1. The combination with a metal container having an open end and an outwardly projecting bead around its open end and a head having a marginal portion adapted to overlie the bead, of a contractile clamping band having a part engageable with the bead to force the band inwardly toward the head as the band is contracted and a part engageable with the head inwardly of the marginal bead engaging portion thereof to press the head against the bead, and means for contracting said band.

2. The combination with a metal container having an open end and an outwardly projecting bead around its open end and a head cupped to provide an upstanding outer portion adapted to fit within the open end of the container, and having a marginal flange adapted to overlie the bead, of a contractile clamping band having a part engageable with the under side of the bead to force the band inwardly toward the head as the band is contracted and a part engageable with the head to press the head toward the bead, and means carried by the band and on the interior thereof within the depression of the head for contracting the same.

3. The combination with a metal container having an open end, an outwardly projecting bead around its open end and a head cupped to provide an upstanding outer portion adapted to fit within the open end of the container and having a marginal flange adapted to overlie the bead, and a packing interposed between the flange and bead, of a contractile clamping band having a part engageable with the bead to force the band inwardly toward the head as the band is contracted and a part engageable with the head

inwardly of the upstanding portion thereof to press the flange of the head toward the bead, and means for contracting said band.

4. The combination with a metal container having an open end and an outwardly projecting bead around its open end and a head cupped to provide an upstanding outer portion adapted to fit within the open end of the container and having a marginal flange adapted to overlie the bead, of a contractible transversely split clamping band in the form of a channel opening laterally with respect to the plane of the band and having an inner flange adapted to engage the head within the upstanding outer portion thereof, and an outer flange inclined inwardly toward the inner flange and adapted to engage said bead to draw the band toward the head and exert an inward thrust thereon when said band is contracted, and means for contracting said band and for holding the same in contracted position.

5. The combination with a metal container having an open end and an outwardly projecting bead around its open end and a head cupped to provide an upstanding outer portion adapted to fit within the open end of the container and having a marginal flange adapted to overlie the bead, of a contractible transversely split clamping band in the form of a channel opening laterally with respect to the plane of the band and having an inner flange adapted to engage the head within the upstanding outer portion thereof, and an outer flange inclined inwardly toward the inner flange and adapted to engage said bead to draw the band toward the head and exert an inward thrust thereon when said band is contracted, and means substantially in the plane of the bead engaging portion of the outer flange for drawing the ends of the band together and fastening the same.

6. The combination with a metal container having an open end an outwardly projecting bead around its open end and a head cupped to provide an upstanding outer portion adapted to fit within the open end of the container and having a marginal flange adapted to overlie the bead, of a contractible transversely split clamping band in the form of a channel opening laterally with respect to the plane of the band and having an inner flange adapted to engage the head within the upstanding outer portion thereof, and an outer flange inclined inwardly toward the inner flange and adapted to engage said bead to draw the band toward the head and exert an inward thrust thereon when said band is contracted, and means carried by the inner flange for drawing the ends of the band together and fastening the same.

for drawing the ends of the band together and fastening the same.

7. The combination with a metal container having an open end and an outwardly projecting bead around its open end and a head cupped to provide an upstanding outer portion adapted to fit within the open end of the container and having a marginal flange adapted to overlie the bead, of a contractible transversely split clamping band in the form of a channel opening laterally with respect to the plane of the band and having an inner flange adapted to engage the head within the upstanding outer portion thereof, and an outer flange inclined inwardly toward the inner flange and adapted to engage said bead to draw the band toward the head and exert an inward thrust thereon when said band is contracted, and means carried by the inner flange and positioned substantially in the plane of the bead engaging portion of the outer flange for the drawing the ends of the band together and fastening the same.

8. The combination with a metal container having an open end and an outwardly projecting bead around its open end and a head cupped to provide an upstanding outer portion adapted to fit within the open end of the container and having a marginal flange adapted to overlie the bead, of a contractible clamping band having parts engaging said bead and said head and adapted to exert an inward pressure on the head when the band is contracted, and means on the interior of the band and lying within the depression of the head for contracting and fastening the band.

9. In a device of the character described, a contractible clamping band in the form of a channel opening laterally with respect to the plane of the band and having an inner substantially cylindrical flange and an outer flange inclined inwardly toward said inner flange, said band being severed at one point and the adjoining ends having lugs rigidly secured thereto and extending inwardly from said inner flange, and a bolt extending through said lugs for tightening the band.

10. In a device of the character described, a contractible clamping band severed at one point and having inwardly extending lugs rigidly secured to adjacent ends, and a bolt extending through the lugs for tightening the band, said lugs being provided inwardly of the bolt with bearing projections on the opposed faces thereof.

In testimony whereof, we hereunto affix our signatures.
